UNITED STATES PATENT OFFICE.

JOHN COSTELLO, OF ATTLEBOROUGH, MASSACHUSETTS, ASSIGNOR OF
ONE-HALF TO JAMES F. SIMMS, OF SAME PLACE.

BUTTON.

SPECIFICATION forming part of Letters Patent No. 363,285, dated May 17, 1887.

Application filed February 14, 1887. Serial No. 227,540. (No model.)

To all whom it may concern:

Be it known that I, JOHN COSTELLO, a citizen of the United States, and a resident of Attleborough, in the county of Bristol and State 5 of Massachusetts, have invented certain new and useful Improvements in Buttons; and I do hereby declare that the following is a full, clear, and exact description of the invention, which will enable others skilled in the art to which 10 it appertains to make and use the same, reference being had to the accompanying drawings, which form a part of this specification, and in which—

Figure 1 is a perspective view, seen from the 15 under side, of my improved button, showing it ready for insertion in the button-hole. Fig. 2 is a similar view of the button, showing it as it appears after being inserted and locked. Figs. 3 and 4 are sectional views taken through 20 the shank of the button in the two positions shown in Figs. 1 and 2. Figs. 5 and 6 are perspective views of a modified form of the button, showing it ready for insertion and as it appears after being inserted and locked; and 25 Figs. 7 and 8 are sectional views taken through the shank of the button in its two positions.

Similar numerals of reference indicate corresponding parts in all the figures.

My invention has relation to that class of 30 buttons having a shank provided at its lower end with a radiating arm, and having the said shank journaled to revolve within a flat shank provided with another radiating arm, so that the arms may be turned to point in the same 35 direction, when they may be inserted through the button-hole, whereupon the head of the button and the inner shank may be turned, bringing the arms to project in opposite directions, securing the button in the hole; and it 40 consists in the improved construction and combination of parts of such a button, as herein-after more fully described and claimed.

In the accompanying drawings, the numeral 1 indicates the head of the button, which may 45 be of any desired shape and material, and which may be ornamented in any desired manner, and from the back of this head projects the inner or revolving shank, 2, which is provided at its lower end with a radially-project-

ing arm, 3, projecting in a plane parallel to 50 the plane of the back of the head, said head, shank, and arm being rigidly secured together.

The stationary arm 4 is preferably of the same shape and size as the revolving arm, and is formed with a flat shank, 5, slotted transversely, so as to form a central bulging strip, 6, and an upper and lower strip, 7, bulging in the opposite direction, the said strips forming a bearing for the revolving shank, and the flat shank and the arm are preferably formed from 55 one plate cut and bent into the shape of the parts.

The upper end of the flat shank is cut out to form two projecting lugs, 8, at the side edges, and these lugs engage notches in the opposite 60 edges of a spring-plate, 10, rigidly securing them together. This spring-plate has slightly downwardly-curved ends, and provided with upwardly-projecting lugs 11 upon one side, 65 near the ends, which lugs may engage corresponding recesses, 12, in the under side of the back-plate, the lugs being preferably formed by punching or depressing the metal of the 70 spring-plate.

It will be seen that when the radiating arms 75 of the shanks are turned to diverge in opposite directions the lugs will engage the recesses or notches, locking the arms and shanks in place in their relative positions, and when the revolving shank and its arm are turned to 80 bring the arms to point in the same direction the lugs will likewise engage the recesses or notches, so that the arms may be locked in these two positions, the springiness of the spring-plate 10 allowing the lugs 11 to be released 85 from the recesses or notches 12, and at the same time holding them sufficiently firmly in the same to prevent the accidental turning of the shank.

The arms are brought to point in the same 90 direction when the button is to be inserted into the button-hole, when the arms and their shanks may be slipped into the hole, and when the arms and shanks have been inserted the revolving shank and arm are turned, the flat 95 shank being held by the edges of the button-hole, and the arms will point in opposite directions, preventing the button from being with-

drawn, the lugs upon the spring-plate holding the arms in their proper positions, resting in the recesses or notches.

In the modified form shown in the last four figures of the drawings the head is provided upon its back with an annular plate or ring, 13, having two diametrically-opposite notches, 14, in its inner edge, and the flat shank is formed with two legs, 15, revolving with their 10 ends within the annular plate, having the outer edges engaging the notches in the edge of the said plate, the said legs and notches performing the same duties as the spring-plate with its lugs and the recesses or notches in the back- 15 plate in the first-described button.

The bearing for the revolving shank is formed in the end of a tongue, 16, cut out of the stationary arm, the bearing for the revolving shank and the head being formed by the 20 annular plate and the legs of the stationary shank at the upper ends of the same.

Having thus described my invention, I claim and desire to secure by Letters Patent of the United States—

In a button, the combination of a flatshank 25 having its middle slotted transversely to form strips bulging in opposite directions, forming a bearing, and having a radially-projecting arm at its inner end, and having projecting lugs at its outer end, a head having a shank revolving within the bearing of the flat shank, and formed with a radially-projecting arm at its inner end, and having diametrically-opposite notches in its back-plate, and a spring-plate secured with notches in its side edges to the 30 lugs upon the end of the flat shank, and having its bulging ends formed with lugs engaging the notches in the back-plate, as and for the purpose shown and set forth.

In testimony that I claim the foregoing as 40 my own I have hereunto affixed my signature in presence of two witnesses.

JOHN COSTELLO.

Witnesses:

PHILIP E. BRADY,
JOHN REYNOLDS.
